UNITED STATES PATENT OFFICE.

CARL G. GROSS, OF MOUNT VERNON, NEW YORK, ASSIGNOR TO EASTERN LABORATORIES, INC., OF NEW YORK, N. Y.

ELECTRIC DRIER.

Application filed April 28, 1925. Serial No. 26,385.

My invention relates to an electric drier of the type wherein the function of drying is accomplished by a volume of air delivered by a blower and heated in its passage to the point of use. The particular form in which I choose to illustrate my invention embodies new and useful features whereby the operation and effectiveness is largely increased and among such features may be mentioned the ability to deliver the air in a multitude of directions according to the position of the object to be dried, an arrangement whereby it is impossible to burn out or damage the device if the delivery of the air should be blocked for any reason, a quick breaking, non-arching switch and other advantages which will be evident from the following description and drawings. While my invention is primarily directed to an electric drier adapted to perform the functions of drying the hands or face of a person, it would be equally applicable to a variety of other uses where a volume of heated air is desired to be directed upon moisture containing objects or places and where that air may be directed in the most efficient way. In the drawings:

Figure 1 is a side elevation, partly broken away, of the cabinet and the complete drier.

Figure 2 is a rear elevation, partly broken away, of Figure 1.

Figure 3 is a section showing the hood between the blower discharge passage and the conduit.

Figure 4 is a part section through the outlet showing its connection to the conduit and to the cabinet.

Figure 5 is a plan view of the switch mechanism.

Figure 6 is a side elevation of Fig. 5 in the contacting position.

Figure 7 is a side elevation of Fig. 5 in the non-contacting position.

Figure 8 is a vertical section through one of the resilient switch contacts.

In Fig. 1, a cabinet with which I enclose my apparatus is shown at 1 which may have usual supports such as 2, a top piece 3 and a hinged door 4 at the rear to provide ready access to the interior and the apparatus.

At 5 is a housing containing a blower fan preferably directly connected to a motor 6 which in this case may be fixed to the housing 5 and the whole held in place by the supports 7. The blower has an intake 55 8 which I show as a plate having screened openings to exclude matter apt to damage the fan. At 5^a is a pet cock or drain which enters into the housing 5 and which may be used to carry off any liquid which may collect in this housing by being poured through the outlet 15 or which may accumulate from other causes so that damage to the blower cannot result from such causes. Affixed to the discharge passage 9 of the 60 blower is a hood 10 which fits over the discharge passage 9 as shown in Fig. 3 and which also connects with the conduit 11. This hood 10 may be attached in a variety of ways, one of which I show in Fig. 3 65 70 where a collar 12 fits over and is seated upon the discharge passage 9 and has spacers 13 against which the hood 10 is held by screws 14. The attachment of the hood 10 to the conduit 11 may be by several means such as a brazed joint in the case of a metallic conduit or a strapped joint if a non-metallic conduit is used, or it may be an integral part of the conduit 11 and formed from it. At the other end of the conduit 11 is an outlet 15 which I connect to the conduit and cabinet as follows. Attached to the conduit 11 is a sleeve 16 which registers with an opening in the cabinet 1 (Fig. 4) and is held in place by bolts 17 in this instance so that 80 the conduit is held in proper position. The outlet 15 has a flange 18 and an extension 19 which fits into the sleeve 16; this extension being provided with an annular groove 20 which is arranged to receive a set screw 90 or pin 21 passing through the sleeve 16. Therefore while the outlet 15 is firmly affixed to the conduit 11, it can be revolved through 360 degrees and the air stream directed to any selected point accordingly. 85 By providing an adjustable outlet, a further flexibility could be obtained in a direction normal to the illustrated plane of rotation. In the discharge passage 9 of the blower is a heating element 22 (Figs. 1 and 2) over and 95

through which the air must pass and which will be heated accordingly. This heating element may be one of many usual types that are electrically heated but in the present instance I prefer to use one similar to the one illustrated in my co-pending application for an electric hair drier, Serial Number 749,691 filed November 13, 1924. It would be equally satisfactory and, in some instances preferable to locate the heating element at some point in the conduit 11 such as at 22^a. In such case the other heating element 22 might or might not be used so that I am not limited to the location of the heating element nor to the use of a single one; the particular arrangement or location being dependent upon circumstances.

The leads (not shown) for supplying current to the motor 6 and the heating element 22 come from the switching mechanism shown in Figures 5, 6 and 7; this mechanism controlling the operation of both the motor and the heating element. The switching mechanism comprises a base 23 which carries two sets of supports 24 and 25. To the supports 24 is pivoted a foot pedal 26 which has an extending lug 27 with pins 28 and a slotted end 29. To the supports 25 is pivoted a switch arm 30 having one end engaging the slotted end 29 of the foot pedal 26 by means of the pin 31 and the other end carrying contacts 32 and 33. On this arm are also laterally extending pins 34. These pins 34 and the pins 28 have extending between them, the extension springs 35 and 36. The contacts 32 and 33 are adapted to seat on corresponding contacts one of which is shown at 37; these contacts being mounted in a supplementary base plate 38 held to this main base 23 in any customary manner such as the bolts and nuts 39 (Fig. 8). Leading to these contacts on the supplementary base 38 are the conductors 40 which come from the posts 41 and 42; the former being connected to one of the main feed wires 43 while the other feed wire 44 goes to a separate post 45. Across the contacts 32 and 33 is a conductor 46 which acts to place these contacts in series with the conductors 39 and 40. From the posts 41 and 45 leads the circuit of wires 47 and 48 and in parallel with this circuit is a second one composed of the wires 49 and 50. One of these circuits leads to the motor 6 and the other to the heating element 22 (Fig. 1) so that it will be seen that the contacts 32 and 33 being in series with the circuits (the wires 44 and 48 being a common wire to both the feed and operating circuits) the switch will control both the heating element and the motor. The contacts 31 and 32 are illustrated in Fig. 8, where the switch arm 30 has a nonconducting insert 51 held in place by a screw 52. Passing through and having a bearing in this insert is a conducting piece

53 with an enlarged end 54 to correspond with the contact 37. The nuts 55 and 56 on the conducting piece 53 not only serve to hold the conductor 46 but also provides a stop for the limited motion of the piece 53 under the action of the spring 57 compressed between the insert 51 and the enlarged end 54.

In the operation of my invention, the apparatus is normally at rest with the switch mechanism in the position shown in Figures 1 and 7. When it is desired to use the drier, the outlet 15 is turned to the required position such as might be downward for drying the hands or upward for drying the face and the foot pedal 26 depressed. This causes the contacts 32 and 33 to close the circuits to the motor 6 and the heating element 22 so that the blower will discharge air through the outlet 15 and this air, in passing over and through the heating element 22 will become heated to the required degree which has been predetermined by proper design. Where the drying operation is complete, the foot is removed from the pedal 26 which allows the springs 35 and 36 to raise both the foot pedal 26 and the switch member 30 and thus break the contacts to shut off the current to the motor and heating element. The detail action of the switch mechanism is as follows, see Figs. 6 and 7. When the foot pedal 26 is depressed, the springs 35 and 36 are extended and the switch arm 30 is pivoted in its support 25 by the action of the pin 31 in the slotted end 29; this pin resting in the lower part of that slot. As the downward motion of the foot pedal 26 continues, it passes through the point where the springs 35 and 36, the pivots in supports 24 and 25 and the pin 31 are in a straight line. As this point of dead center is passed the springs have a leverage upon the switch arm 30 which is accentuated by the pin 31 going to the top of the slotted end 29 and this leverage allows the springs to throw the switch arm quickly downward with accelerated motion upon the contacts shown as at 37 and all tendency for arcing to occur in the closing operation is obviated. The switch is then in the position shown in Fig. 6. When the pressure on the foot pedal 26 is released, the slotted end 29 drops under the action of the springs 35 and 36 and carries with it the pin 31 of the switch arm 30. This raises the contacts 32 and 33 but the contact 37 and the enlarged end 54 remain together momentarily due to the spring 57 (Fig. 8). This momentary period of travel, which is equal to the time of travel of the arm 30 between 51 and 55 of Fig. 8, allows the switch arm 30 to gather speed and when the separation of contacts occurs by the insert 51 abutting the nut 55, it comes sharply and evenly so that there is practically no

tendency for an arc to form in the breaking operation.

The speed of travel of the contact 32 is a function of the ratios of leverage of the 5 foot pedal 26 and the arm 30 so that these may be adjusted to the maximum practical speed of the contact 32 and the distance between 51 and 55 so proportioned that no breaking of the contacts occurs until the 10 springs 35 and 36 are past the dead centers of the foot pedal 26 and arm 30 so that the breaking is sharp and no arcing takes place. The upward travel of the foot pedal 26 and the switch arm 30 continues until they assume 15 the position shown in Fig. 7. Therefore this switch mechanism provides a positive, rapid and effective quick breaking device of obvious and advantage to which may be added the one that by having contacts 20 such as 32 and 33 in series a doubling of that contacting occurs which is a further deterrent to arcing and conducive to proper operation of the switch. It will be noted that the hood 10 shown in Figs. 1 to 3 inclusive 25 has a distinct function as a safeguard. Were the conduit 11 directly attached to the discharge passage 9 of the blower and the blower going, a stoppage in the conduit—such as a hand placed over the outlet 30 15 would stop the flow of air but not the accumulation of heat from the heating element 22 and it would follow that the accumulated heat would tend to burn out or otherwise damage the apparatus. By placing this 35 hood 10 as I do, the air can escape from it in the event of a block in the conduit 11 and the blower continue to run without danger of damage.

From the foregoing it will be clear that, 40 while I have described my invention in its preferred form, many changes and variations may be made without departing from the spirit thereof and all such changes and variations I desire to include within the 45 scope of my claims.

I claim:

1. In an electric drier, the combination of a blower having a discharge passage, a conduit covering the end of said discharge passage and spaced therefrom, and a heating element.
2. In an electric drier, the combination of a blower having a discharge passage, a conduit covering the end of said discharge passage and spaced therefrom, a heating element, and a revolvable outlet on the outer end of said conduit.
3. In an electric drier, the combination with a blower having a discharge passage, and a heating element, of a conduit having a revolvable outlet on one end and on the other end a hood adapted to extend downwardly over the discharge passage of the blower.
4. In an electric drier, the combination

with blower having a discharge passage, driving means and controlling means for said blower, of a conduit having a hooded end covering the discharge passage and the other end terminating in a revolvable outlet. 70

5. In an electric drier the combination of a blower, having a heating element associated therewith, a motor to drive the blower and switching mechanism to control the motor and the heating element which comprises 75 a pivoted foot pedal adapted to actuate a pivoted switch arm, a tension spring connecting the two and so positioned as to accelerate the movement of the switch arm toward its contacting position and normally 80 to hold the switch arm inoperative.

6. In an electric drier the combination of a blower having a heating element associated therewith, a conduit to conduct the blower discharge to a given point and means 85 between said blower and said conduit to permit escape of the blower discharge in the event of a stoppage in the conduit.

7. In combination with a drier having a motor, a blower and a heating element associated with said blower, a switch mechanism common to said motor and said heating element for controlling said motor and said heating element and comprising a pivoted actuating member, a pivoted switch arm engaged by said actuating member, a tension spring connecting said actuating member and said switch arm, and a plurality of resilient contacts on said switch arm adapted to simultaneously register with their corresponding contacts in the switch mechanism. 90

8. In an electric drier the combination of a blower having a heating element connected therewith, a hooded conduit covering the discharge passage of the blower and 105 having its other end terminating in a revolvable outlet, a switching mechanism to control the blower and the heating element; said switching mechanism including means carrying resilient contacts adapted to be 110 accelerated in the contact making and breaking movements by positive means connecting the contacting carrying means and the actuating means therefor.

9. In an electric drier, a blower having a 115 discharge outlet, a hood over the discharge outlet of the blower and a conduit leading from said hood to a desired point.

10. In a drier, means to discharge a volume of air through a discharge passage, 120 means to receive that volume of air and having an opening larger than said discharge passage and means to conduct the air from the receiving means to a given point.

11. In a drier, a blower, a hooded member 125 and a conduit, said hooded member having an opening larger than the discharge outlet of the blower and arranged to receive the air therefrom and divert it to said conduit.

12. In an electric drier, a blower, a con-

duit, a hood over the discharge outlet of said blower and connected to said conduit and a heating element in said conduit adapted to heat the air from said blower.

5 13. In an electric drier, a blower and a conduit, said conduit having an end enlarged beyond the area of the discharge out-

let of said blower and adapted to receive the discharge thereof.

In testimony whereof, I have signed my 10 name to this specification this 20th day of April, 1925.

CARL G. GROSS.
